UNITED STATES PATENT OFFICE.

HERMANN WALTER GRÄNZ, OF CHEMNITZ, GERMANY, ASSIGNOR TO THE FIRM OF SCHUBEET & SALZER MASCHINENFABRIK, AKTIENGESELLSCHAFT, OF CHEMNITZ, GERMANY.

SEAMLESS STOCKING OR SOCK AND METHOD OF MAKING SAME.

1,228,664.

Specification of Letters Patent.

Patented June 5, 1917.

Application filed May 28, 1913. Serial No. 770,371.

To all whom it may concern:

Be it known that I, HERMANN WALTER GRÄNZ, a citizen of the German Empire, and residing at Chemnitz, Germany, have invented certain new and useful Improvements in Seamless Stockings or Socks and Methods of Making Same; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to improvements in seamless stockings or socks and the method of making same, and more particularly in seamless stockings or socks having cap-heels and French toes on Lamb's knitting machine and the object of the improvements is to provide a stocking or sock which is made in one cycle of operations without removal of the loops and consequently without turning the stocking or sock.

To the manufacture of a correct stocking there belong the narrowed leg, the heel, the heel-cap, the foot and the toe. It is well known to make the seamless and narrowed leg, the heel-cap and the foot on Lamb's knitting machine, but it is new to work the entire stocking including the capped heel and the toe seamless and without removal of the loops from the needles, consecutively in one cycle of operations and without turning the stocking.

Heretofore the manufacture of seamless capped heels has caused particular difficulties which were particularly due to the loops being pulled when widening. This pulling of the loops became so great that at last the seizure of the loops by the needle-bars became uncertain and rupture of the loops readily occurred.

On the other hand, the manufacture of the toe was connected with the following difficulties. As the narrowing strip always occurred heretofore at the right and left at the end of the needle-bars, the foot-loops and the heel-loops each had to be located in one needle-bar when making the toe, because otherwise a "French" toe was not obtained. Therefore, as the stocking was located in another position in the machine, in which, for

example, divided groups of needles were used for making the heel, it had to be brought into the correct position for making the toe by removing the loops from the needles and turning the stocking.

My improved method enables a stocking to be made in which the pulling of the loops during the formation of the heels is avoided, and simultaneously a French toe is obtained without removing the loops from the needles and without turning.

The pulling of the loops is avoided when making the heel by alternately first knitting two rows half open, and then knitting one complete circular row until the heel is finished; the French toe is obtained by placing the narrowing strips in the middle of the needle-bars.

For the purpose of explaining the invention, an example of a stocking in various stages of the manufacture and apparatus used in the manufacture have been shown in the accompanying drawings, in which the same letters of reference have been used in all the views to indicate corresponding parts.

In the drawings—

Figure 1 is a side view showing a finished stocking.

Figs. 2 and 3 are diagrammatical perspective views illustrating the old method of making the heel portion of a stocking.

Figs. 4 to 7, are similar views illustrating my improved method of making the heel of the stocking.

Figs. 8 to 13, are detail views showing on a much enlarged scale the formation of the loops in successive stages of the manufacture of the heel.

Fig. 14, is an enlarged view showing the loops of the heel and of the adjacent part of the instep in distorted form.

Fig. 15 is an enlarged view showing the loops illustrated in Fig. 14 as they really appear.

Fig. 16 is a diagrammatical view showing the tickler which is used in the manufacture of my improved stocking, and

Figs. 17 and 18 are diagrammatical views illustrating two stages of the manufacture of the toe.

In order that my improved method may be more clearly understood, I shall at first briefly describe the old method of making the heel portion of a stocking, so that in

describing thereafter my improved method the difference will be clearly understood.

Heretofore, in the manufacture of a stocking the leg was at first completed to the section 1—2—3—4—1, in Fig. 2, whereupon knitting was continued exclusively with the loops 2—3—4 up to the loops 5—6—7 so as to form the heel. Thereupon the heel cap was made, and finally the foot was knitted.

10 While on the machine the part of the stocking shown in Fig. 2 and completed up to the loops 5—6—7 assumes the form shown in Fig. 3, in which figure the corresponding points of the stocking have received the same numerals of reference. From an inspection of Figs. 2 and 3 it will readily be understood, that the loops located at the border line are strained in such a way, that the durability of the stocking is impaired.

20 The strain on the loops is such, that they are liable to be torn even in the course of the manufacture.

My improved method is distinguished from the method referred to in this respect, that instead of knitting at first exclusively the heel, and beginning thereafter the knitting of the instep, the said parts are simultaneously knitted.

In Figs. 4 and 5, I have illustrated the heel portion of the stocking made according to my improved method in a similar way as in Figs. 2 and 3. After the leg has been knitted up to the section 1'—2—3'—4'—1', I continue to knit at the same time the heel up to the line 5'—6'—7' and the foot up to the line 5'—8'—7'.

For this purpose I knit alternately half open and full circular rows, as is shown in a diagrammatical way in Fig. 6.

40 For carrying my process into practice the knitting machine is provided with four broad transfer combs i_1 — i_4 (Fig. 16) which can move toward and away from one another in the directions indicated by the arrows. The right-hand transfer combs i_3 , i_4 are each provided with a displaceable transfer point a and a' , respectively.

When the stocking (Fig. 1) is closed in a circle narrowed at the calf and finished up to the beginning of the heel, the loops still suspended on the needles are divided into two groups, namely into loops for making the foot and into those for making the heel. This is done on both the needle-bars, so 55 that the loops for the foot and heel lie in two groups. The heel is therefore formed on both needle-bars.

In Fig. 8 only some of the loops of the foot A and of the heel B of the front needle-bar are represented.

Fig. 9 illustrates the knitting operation in a diagrammatical way, and Figs. 10 to 13, illustrate the same by representing the loops. In Fig. 9 the full lines represent the 65 row of loops of the front needle bar, and

the dotted lines those of the rear needle bar. Row I represents the last circular row of the leg which corresponds to the line 1'—2'—3'—4'—1' of Fig. 4. At first the needles for knitting the instep remain inoperative, while on the needles B of the heel knitting takes place from the right to the left (row II) and back again from the left to the right (row III), and thereafter in the same way on the rear needle bar from the right to the left (row IV), and back again from the left to the right (row V).

70 Before the return of the thread carrier from left to right, thus before the change from the first to the second row, the transfer point a advances (Figs. 10 and 16) and remains stationary over the first latch-needle for the foot. The thread consequently forms a loop b around this needle. The same operation is repeated on the rear needle-bar when the transfer point a' (Fig. 16) advances.

75 Now when the two transfer points a , a' carry loops, in order to be able to pass over the knocking-over comb these transfer points rise somewhat from the needles located below and move one division to the right, as indicated in dotted lines in Fig. 11. This movement takes place in order to expose the edge loop of the foot for being 80 lifted.

85 All the loops of the foot needles are now widened one needle division to the left, thus toward the outside, as will now be described. (Fig. 12.)

90 While the transfer points lie on the foot needles, and in order to seize the loops, the movable transfer points, which now lie in the dotted line position, Fig. 11, are moved back so far that the loops b remain suspended thereon, and the adjacent heel loops below are not engaged. Now the transfer combs i_3 and i_4 move one needle to the left. As the movable transfer points a , a' are mounted on the transfer combs i_3 , i_4 , the 100 loops b suspended on the transfer points a , a' , are carried to the left by the movement of said combs i_3 , i_4 , over onto the needles at the right hand edge of the foot portion, Fig. 12, said edge needles having been 105 previously freed from their loops.

110 After the widening of the foot-loops a row is knitted in a circle α , α (Fig. 13) on the front and rear needle-bar, thus the loops of all the needles provided with loops are 115 sunk, the thread carrier moving from right to left and back again. The thread carrier therefore is now located at the right-hand of the machine and again begins the half-open knitting in the above-described manner. This operation alternates with knitting a complete round until the heel is finished.

120 Owing to the loops formed during the half-open knitting being suspended on the 130

foot needles which become empty owing to widening, a thoroughly neat connection *y* (Fig. 1) is made between the foot and the heel, and simultaneously the tension or excessive distortion of the loops is done away when making the round row.

When the heel is finished as far as the line *z* in Fig. 1 the cap is made by knitting half-open in known manner with only a small number of heel needles located at the right-hand end of the needle-bars, and after each two rows, front and rear, these meshes are shifted one needle division inward to the first foot needle *c* (Fig. 1).

15 The foot is thereupon made up to the toe.

Now in order to obtain the narrowing strips *f* (Fig. 1) without turning and without removal of the loops, as indicated in this figure, *i. e.* in order to obtain a toe having French narrowing, in contradistinction to the process customary heretofore the narrowing strip is made in the middle of each needle-bar by the loops *g* and *h* being suspended toward the inside. For this purpose the above-mentioned broad transfer combs are employed, two of them being used for each needle-bar. The process is carried out as follows:

The strip *f* is formed for example out of six loops. The loops *g* and *h* are lifted from the broad transfer combs *i*₂ and *i*₄ and narrowed one needle division inward, whereupon the transfer combs return empty one needle division, thus returning into their original position. The same operation is repeated on the rear needle-bar by moving the transfer combs *i*₁ and *i*₃.

When there are only six loops left at last, as indicated in Fig. 18, the two loops to the right and left are narrowed in succession on the two middle needles, so that only two loops remain over which are fastened with a needle.

In the above-described process of making the heel it was assumed that the foot loops were widened outward. It is however possible to widen the heel loops outward, in which case the emptied needles will be occupied with a loop which is formed over the displaceable transfer points. In this case the displaceable transfer points will be arranged at the left in the transfer combs *i*₃ and *i*₄. Otherwise the process is carried out in exactly the same manner as described above, *i. e.* after each widening a complete circular row is knitted.

I claim:

1. The herein described method of making stockings or socks, which consists in first knitting the leg on two oppositely disposed needle bars, thereupon simultaneously knitting the heel and the adjacent part of the foot with one part of the foot and heel loops carried by each of the said needle bars, knitting the foot portion, and finally knit-

ting the toe while narrowing the loops located on each needle bar at parts intermediate the ends thereof.

2. The herein described method of making stockings or socks, which consists in first knitting the leg on two oppositely disposed needle bars, thereupon simultaneously knitting the heel and the adjacent part of the foot with one part of the foot and heel loops carried by each of the said needle bars, knitting the heel cap, knitting the foot portion, and finally knitting the toe while narrowing the loops located on each needle bar at parts intermediate the ends thereof.

3. The herein described method of making stockings or socks, which consists in first knitting the leg on two oppositely disposed needle bars, thereupon simultaneously knitting the heel and the adjacent part of the foot with one part of the foot and heel loops carried by each of the said needle bars, knitting the foot portion, and finally knitting the toe while narrowing the loops located on each needle bar at two parts intermediate the ends thereof and at a distance from each other.

4. The herein described method of knitting a stocking or sock, which comprises alternately knitting at least one half open row of the length corresponding to the breadth of the heel and a closed circular row corresponding to the circumference of the heel and adjacent part of the foot, all the half open rows being made on the same number of needles.

5. The herein described method of knitting a stocking or sock, which comprises alternately knitting at least one half open row of the length corresponding to the breadth of the heel and at least one closed circular row corresponding to the circumference of the heel and adjacent part of the foot, and after completing the heel and adjacent part of the foot knitting the cap.

6. The herein described method of knitting a stocking or sock, which comprises alternatively knitting at least one half open row of the length corresponding to the breadth of the heel while adding at each end of the half open row at least one loop and at least one closed circular row corresponding to the circumference of the heel and adjacent part of the foot and including the added loops.

7. The herein described method of knitting a stocking or sock, which comprises alternately knitting at least one half open row of the length corresponding to the breadth of the heel while adding at each end of the half open row at least one loop and at least one closed circular row corresponding to the circumference of the heel and adjacent part of the foot and including the added loops, after completing the heel and adjacent part of the foot knitting the toe.

cap, and thereafter continuing the knitting of the foot.

8. The herein described method of knitting a stocking or sock on Lamb's knitting machine, which comprises first knitting the leg with the loops hung on two oppositely arranged needle bars, successively knitting on one part of each of the bars at least two rows of loops to form a part of the heel 5 while adding a loop between said rows at each end thereof and knitting at least one complete circle on the needle bars to form a part of the foot and heel, knitting the cap, knitting the foot, and finally knitting the toe while gradually narrowing on both bars 10 at parts intermediate the ends thereof and on each bar at a distance from each other to form a strip.

9. The herein described sock or stocking 20 in which the heel and adjacent part of the foot consists alternately of at least one half open row of loops extending the whole breadth of the heel and at least one complete

circular row extending over the heel and adjacent part of the foot.

10. The herein described sock or stocking in which the heel and adjacent part of the foot consists alternately of at least two half open rows of loops extending the whole breadth of the heel with an additional loop 25 added at each end and at least one complete circular row extending over the heel and adjacent part of the foot.

11. The herein described method of knitting a seamless stocking or sock, which comprises simultaneously knitting the heel and the adjacent instep portion of the foot, and thereafter knitting the heel cap.

In testimony that I claim the foregoing as my invention, I have signed my name in 30 presence of two subscribing witnesses.

HERMANN WALTER GRÄNZ.
